ATTORNEY.

UNITED STATES PATENT OFFICE

MINNIE MEYER, OF NEW YORK, N. Y., ASSIGNOR TO GOLO SLIPPER COMPANY, INC., OF NEW YORK, N. Y., A CORPORATION OF NEW YORK

SANDAL

Application filed March 24, 1932. Serial No. 600,941.

This invention relates to improvements in sandals and more particularly in sandals in which the vamp portion is made of a series of interlocking or interengaging straps.

5 A particular object of this invention is to provide an improved sandal in which the upper or vamp portion is made of straps constructed of textile material and in which the straps will be so constructed so that their 10 edges will be non-fraying in character.

A further object of this invention is to provide an improved sandal having the upper or vamp portion made of a series of interlocked or interlacing straps in which the 15 straps are all of non-fraying construction and may be made with a minimum of expense.

Further objects of the invention will be apparent from the specification and drawing in which Fig. 1 is a perspective view of a new 20 and improved sandal embodying my invention.

Fig. 2 is a perspective view of a portion of one of the individual straps used in the sandal shown in Fig. 1, showing the method of making said individual straps.

Fig. 3 is a cross-sectional view along the line 3—3 of Fig. 2.

10 is the sole of the sandal, 11 is the heel and 12 is the counter having the strap portion 13. 14 designates the individual straps, each having the outer and upper layer 15 and the reinforcement 16 with turned-over edges 17. 18 indicates the lines of stitches joining the upper member 15 to the lower member 16.

The straps 14 are joined to the sole 10 in any improved manner and the method by which they are connected to the sole forms no part of my invention.

40 I prefer to use a textile strip with a selvage or ribbon edge for the upper layer of the strap, as the use of such a strip results in great economy of production and gives a finished strap with edges non-fraying in construction and of pleasing appearance.

It has hitherto been the custom to make such straps (but not for use in making a shoe) from sheet fabric from which the strips 15 have been cut by hand or have been 50 stamped by means of dies. Where strips of

this character have been used, made from sheet fabric, it has been necessary to finish the opposite edges of the strips, the customary manner being to turn under the edges of the strips in alignment with the turned-over edges of the reinforcement on the bottom and to sew the upper strips and reinforcements together with a double parallel seam on the opposite edges of the strap. This has resulted in increased thickness of the strap 55 which is avoided by using a strip provided with ribbon edges.

The strips 15 are formed with selvages, so that their edges are non-raveling and of single thickness.

For reinforcement in the straps 14 shown herein, I employ a rubberized fabric cut into appropriate strips with turned-over edges 17, and these strips 16 of rubberized fabric are sewn to the upper layer 15 as shown in 70 the drawing.

Changes may be made in the form of reinforcement used and in the method of attaching same to the upper layer 15, and other changes may be made in the form of the construction of these straps 14 without departing 75 from the spirit of my invention.

What I claim is:

1. A shoe or the like having a sole and a vamp portion, said vamp portion comprising 80 a series of independent straps which loosely cross each other and which are connected to said sole at separated points thereof, said straps comprising upper layers of textile material having selvaged edges of substantially the same thickness as the body portions thereof, said straps having reinforcing members applied wholly to their under faces, said reinforcing members having longitudinal turned edges which abut the under 85 faces of said textile layers.

2. A shoe or the like having a sole and a vamp portion, said vamp portion comprising 90 a series of independent straps which loosely cross each other and which are connected to said sole at separated points thereof, said straps comprising upper layers of textile material having selvaged edges of substantially the same thickness as the body portions thereof, said straps having reinforcing 100

- members applied wholly to their under faces, said reinforcing members having longitudinal inturned edges which abut the under faces of said textile layers, the width of a 5 reinforcing member being substantially the same as that of the associated upper layer.
3. A shoe or the like having a sole and a vamp portion, said vamp portion comprising a series of independent straps which loosely 10 cross each other and which are connected to said sole at separated points thereof, said straps comprising upper layers of textile material having selvaged edges of substantially the same thickness as the body portions 15 thereof, said straps having reinforcing members applied wholly to their under faces, said reinforcing members having longitudinal inturned edges which abut the under faces of said textile layers, said reinforcing members 20 being made of rubberized fabric.

In testimony whereof, I affix my signature.
MINNIE MEYER.
